DOORLATCH

**Holden W. Rightmyer, Toledo, Ohio, assignor to
The American Swiss Company, Toledo, Ohio, a
Corporation of Ohio**

Application October 27, 1930. Serial No. 491,378

3 Claims. (Cl. 292—164)

This invention relates to door latches, but more particularly to door latches adapted for automobiles in which the handle is positioned on the outside of the door for withdrawing the latch bolt, and another handle is positioned on the inside of the door operable independently of the outside handle for withdrawing the latch bolt.

An object of this invention is to produce a simple and efficient door latch having the new and improved features of construction, arrangement and operation hereinafter described.

For purposes of illustration, but not of limitation, the invention is shown in the accompanying drawing, in which:

15 The figure is a side elevation of the door latch, the remote control mechanism being omitted, but so much of the mechanism being shown as to enable those skilled in this art readily to build and operate the same.

20 The illustrated embodiment of the invention comprises a case plate 1 having an upturned face plate 2, through which projects the head 3 of a latch bolt 4, which is normally held in latching or projected position by a spiral spring 5, one end of which is fixed to the case plate, and the free end 6 of which abuts against a downwardly turned lug 7 on the bolt plate 4. The latch bolt 4 may be retracted from outside by a roll back 8, which is journaled respectively on the case plate 1 and roll back cover plate 9, the latter being suitably secured by tabs 10 extending through openings in the case plate and bent over on the rear side thereof. The roll back 8 is provided with a non-circular opening 8^a to receive the usual handle spindle for operating the same.

An extension 11 on the bolt plate 4 terminates adjacent the roll back 8. Interposed between the free end of the extension 11 and the roll back 8 is an upturned end 12 of a rectilinearly slidable plate 13. The plate 13 is guided in its longitudinal sliding movements by a headed pin 14 on the case plate 1 cooperating with an elongate slot 15 in the plate 13. The upper edge of the slidable plate 13 also engages a wall of the cover plate 9, which assists in guiding the movement thereof.

The bolt plate 4 is formed with a rearward extension 15, which is slidable over an embossed part 16 of the case plate 1 and is guided in its longitudinal movements by a headed pin 17 secured to the embossed part 16 in cooperation with an elongate slot 18 formed in the extension 15. Connected to the rear end of the extension 15 is a remote control strap or link 19, which is formed with a longitudinally elongate slot 20 into which extends a headed pin 21 on the bolt ex-

tension 15. This connection between the strap 19 and the bolt plate affords lost motion of the strap in non-bolt retracting direction when the latch bolt is in its projected or latching position.

The end of the strap 19 is provided with a curved surface 22 engageable with a depending arm 23 of a substantially L-shaped lever 24. The lever 24 is pivoted at 25 to the case plate 1, and a spring 26 having one end hooked into the embossed part 16 and the opposite end into the arm 23 of the lever and the central portion wound about the pivot 25, holds the lever in normal position with the opposite arm 27 in engagement with the embossed part 16. The embossed part 16 forms a stop for limiting the movement of the arm 27, thereby holding the depending arm 23 in the proper position to be engaged by the rounded end 22 of the strap 19.

The outer end 28 of the slide member 13 is curved and the outer end of the lever arm 27 is similarly curved. It will be obvious that when the latch bolt is in its projected or latching position the strap 19 may be moved in non-bolt retracting direction, whereupon the lever 24 will be swung in a clockwise direction against the tension of the spring 26 so that the arm 27 is substantially in alignment with the slidable plate 13. When the parts are in this position retraction of the latch bolt by the roll back 8 is prevented since any effort exerted by the roll back to withdraw the latch bolt is transmitted through the slidable plate 13 to the arm 27 of the lever 24 and thence to the pivot 25. So long as the parts remain in this position actuation of the outside bolt retracting means is blocked. It should be observed that the pivot 25 is positioned directly in the line of movement of the plate 13.

When the remote control strap 19 is moved to the right of the figure the L-shaped lever 24 is released and the spring 26 returns it to normal position. After the lever 24 has returned to its normal position further movement of the strap 19 serves to retract the latch bolt.

An outstanding characteristic of this invention resides in the provision of a plate, or similar member, which is movable over the latch bolt with the roll back and a bent lever, which may be actuated by a remotely controlled element for actuating the same into such position as to block movement of the said member, thereby to dog or block movement of the roll back.

It is to be understood that I have shown and described an embodiment of the invention which is the best form known to me at the present time, and numerous changes in details of construction, arrangement and operation may be effected with-

out departing from the spirit of the invention, especially as defined in the appended claims.

What I claim as new and desire to secure by Letters Patent is:

- 5 1. A door latch comprising a case plate, a tensioned latch bolt movable in the plane of said case plate, a roll back for retracting said latch bolt, inside means for retracting said bolt including a longitudinally movable plate having lost motion in non-bolt retracting direction when said bolt is in projected or latching position, and means for dogging said roll back by the lost motion of said plate, said means comprising a plate directly abutting said roll back on one side and 10 said bolt on the opposite side whereby said bolt is retracted by said roll back through said plate, means to guide movement of said plate over said case plate, and a bent lever movable by said lost motion into position to block movement of said 15 plate.
2. In a door latch having a case plate, a spring-tensioned latch bolt movable in a direction parallel to the plane of said case plate, and inside and outside means for retracting said latch bolt, said inside means having lost motion in non- 20 plate.
- 25 3. In a door latch having a case plate, a spring-tensioned latch bolt movable in a direction parallel to the plane of said case plate, and inside and outside means for retracting said latch bolt, said inside means having lost motion in non-

bolt retracting direction when said latch bolt is in latching position, a plate slidable over said case plate and disposed between said outside means and bolt, said plate being movable by said outside means, and a pivoted lever arranged to be moved in one direction by said lost motion into abutting relation to the opposite end of said slidable plate, thereby to dog said roll back.

3. In a door latch, a case plate, a spring-tensioned latch bolt movable in a direction parallel to the plane of said case plate, an outside operated roll back for retracting said bolt, inside operated means for retracting said bolt including a longitudinally movable link disposed substantially in alignment with said bolt and having lost motion relatively thereto when said latch bolt is in latching position, a plate slidable over said case plate and having a portion thereof disposed between said outside retracting means and bolt and movable by said outside means, and pivotally mounted means associated with said link and movable in one direction by said lost motion into abutting relation to said slidable plate, thereby to dog said roll back.
